CYLINDER FOR OPPOSED-PISTON INTERNAL COMBUSTION ENGINES

Joseph Barraja-Frauenfelder, Upper Montclair, and Oscar G. Schrom, Montclair, N. J., assignors to American Locomotive Company, New York, N. Y., a corporation of New York

Application February 20, 1943, Serial No. 476,590

2 Claims. (Cl. 123—173)

This invention relates to a power cylinder for an internal combustion engine of the opposed-piston type.

In engines of the aforesaid type it is customary to reinforce the liner adjacent the combustion chamber, as by means of an externally encircling integral collar forming a part of the liner. When the cylinder liner is jacketed for the circulation of water or other cooling medium, means are usually provided in the collar permitting passage of cooling medium therethrough, as for instance a series of bores extending through the collar, the means forming part of the circulating system for the cooling medium and serving to cool the reinforced portion of the liner.

The object of the present invention is to provide a cylinder liner, for an engine of the aforesaid type, of an improved construction for more satisfactorily circulating the cooling medium, and particularly for more efficiently cooling a reinforced portion of the liner adjacent the combustion chamber of the cylinder.

Referring to the drawing forming a part of this application, Figure 1 is a fragmentary sectional view of the cylinder assembly of an engine embodying the present invention, taken on the line I—I of Fig. 2, two pistons being shown fragmentarily in section; Fig. 2 is a sectional view of the cylinder assembly of Fig. 1, taken on the line II—II thereof; Fig. 3 is a plan view of a portion of the cylinder liner of Fig. 1; Fig. 4 is a view similar to Fig. 3, showing a modified construction; Fig. 5 is an enlarged section on the line V—V of Fig. 4; and Fig. 6 is a longitudinal central sectional view of a portion of the cylinder liner at a stage in the process of its manufacture.

The invention relates to internal combustion engines of the opposed-piston type generally. The cylinder assembly of such an engine is shown in the accompanying drawing but only to an extent sufficient for a clear understanding of the present invention.

The cylinder assembly comprises a cylinder liner 1 and a jacket 2. The liner is provided with axially-spaced integral collars 3 which the jacket snugly engages, the collars 3 and jacket having aligned orifices providing ports 4.

The cylinder is provided with opposed pistons 5—5 shown in Fig. 1 in their outermost positions. The transverse center plane of the cylinder (cylinder liner) is indicated by a dot-dash line *a*. When the pistons are in their outermost positions, one at each side of and spaced from the plane *a*, they, together with the portion of the liner in the space therebetween, define the com-

bustion chamber, all in the usual manner, the engine thus far described being conventional. The plane *a* is also the transverse center plane of the cylinder combustion chamber.

5 In the manufacture of the cylinder liner of the present invention an integral collar *b* is formed externally on the liner with its transverse center plane in the plane *a* (see Fig. 6). It has a central cylindrical peripheral portion *c* and at each end thereof a frusto-conical portion *d*, the portions *c* and *d* being connected by concave fillet-like portions *e*. The collar *b* may be formed by suitably machining the liner, or the liner may be a casting or forging with the collar *b* forming part of the casting or forging as the case may be. It is old, as aforesaid, to provide a collar for the liner adjacent the cylinder combustion chamber, and the manner in which it is provided on the liner forms no part of the present invention.

10 The present invention comprises a liner having a circumferential row of fins on its outer surface adjacent the cylinder combustion chamber, the fins being spaced to provide passages for the flow of the cooling medium. The fins are preferably formed by cutting or machining the collar *b*, as will later more fully appear.

15 Referring to Figs. 1, 2 and 3, the liner is provided with a circumferential row of fins 6, the fins being separated one from another by spaces 7. The fins 6 and the spaces 7 cross the plane *a*, and extend therefrom at each side thereof. They are disposed adjacent the cylinder combustion chamber and extend in a direction axially of the liner.

20 The fins 6 are formed from the collar *b* by cutting the collar away to provide the spaces 7. The fins comprise facial portions *c'*, *d'* and *e'* corresponding respectively to the portions *c*, *d* and *e* of the collar *b*.

25 The jacket 2 snugly engages the fins at the portions *c'* and bridges the spaces 7 therebetween, the spaces thereby providing a circumferential row of passages 8. At each end of the row of fins the jacket 2 is spaced from the liner whereby chambers 9 and 10 are provided. There are other chambers 11 and 12 at the outer ends of the collars 3 which are provided one with an inlet and the other with an outlet (not shown) for cooling medium in any preferred and well-known manner. The chamber 9 is connected with the chamber 11, and the chamber 10 is connected with the chamber 12, by passages 13 formed in the collars 3 in the walls separating the adjacent ports 4. Preferably a passage 13 is formed in each separating wall. The direction of

flow of the cooling water (or other medium) is optional. Assume it is in the direction of the arrow in Fig. 1. The water then flows from chamber 11 through the adjacent passages 13 to the chamber 9, then through the passages 8 to the chamber 10, then through the adjacent passages 13 to the chamber 12.

The water thus flows through the passages 8 in heat exchange relation with the fins 6 and the portions of the liner between the fins.

The fins 6 and spaces 7 are of substantial lengths and heights and they are suitably proportioned as to width about the circumference of the liner to provide ample heat exchange between the fins, liner portions therebetween, and the cooling water flowing through the passages 8. Consideration however is given in forming the fins to give them sufficient width to afford the required reinforcement for the liner at the combustion chamber portion thereof where the fins are located.

A further feature of the invention is to provide the liner portions which are within the spaces 7 between the fins of gradually decreasing thickness from the outer ends of the spaces toward the center, with a minimum thickness at the plane *a*. This is accompanied by a corresponding gradual approach of the bases of the fins toward the interior face of the liner, this approach being from the ends of the fins toward the plane *a*, and being of a maximum degree at the plane *a*, that is to say, they approach nearest to the liner interior face at the plane *a*. These characteristics of the liner portions within the spaces 7, and of the fins, tends toward better heat transfer adjacent the combustion chamber where the temperature is the highest.

The fins 6 and spaces 7 may be formed in various ways, for instance a revolving circular cutter (not shown) may be employed, in which case the cutter will be started at one end of the collar *b* and fed along the collar to the other end. This will be repeated if necessary until a space is completely formed. By repeating this operation at the desired circumferential intervals, the spaces and fins, as in Figs. 1, 2 and 3, extend axially of the liner, the cutter will obviously likewise be fed along the collar axially of the liner.

The circular cutter is well adapted for providing the aforesaid gradual decreasing thickness in the wall of the liner within the spaces and the gradual approach of the bases of the fins toward the inner face of the liner. All that is necessary to accomplish this when employing a revolving circular cutter is to feed it gradually toward the liner axis *x* as it is moving from an end of the collar *b* toward the plane *a* and to feed it gradually away from the liner axis *x* when it is moving from the plane *a* toward the opposite end of the collar *b*.

Figs. 1, 2 and 3 show fins 6 and spaces 7 having the aforesaid characteristics and which may be formed by a revolving circular cutter operated as has been described. Here the outer faces of the liner portions in the spaces and the bases of the fins are gradually inclined toward the axis *x* from their outer ends to the center or plane *a*, as is clearly shown by the lines *f*—*f*, Fig. 1, and *g*—*h*, Fig. 2, the lines *f*—*f* being shown as curved although they may be straight, meeting at the plane *a* to form an angle, depending upon the manner of feeding the cutter.

Figs. 4 and 5 show a modified construction.

Here the liner 14 is provided with fins 15 and intervening spaces 16 which are disposed at an angle to its axis *x* of its cylinder. The method formerly described of forming the fins 6 and intervening spaces 7 shown in Figs. 1 to 3, where the revolving circular cutter was moved toward and away from the axis *x* as it was passed along the collar *b* from end to end thereof, is not adapted for forming the fins 15 and intervening spaces 16. Here a simpler method is followed. The cutting tool, as for instance the revolving circular cutter, is moved in a straight path through the collar *b*, in a plane parallel to the axis *x* and at an angle to the axis similar to the angle of the corresponding fin 15 and space 16 to be formed.

This method of producing the fins and intervening spaces instead of producing the lines *f*—*f*, which may be curved or straight as aforesaid, the straight lines forming an angle at the plane *a*, produces the straight line *j* extending from end to end of the fin 15 and adjacent space 16. Nevertheless the fins 15 and spaces 16 have the same advantage as the fins 6 and spaces 7 in that the outer face of the liner portions in the spaces and the bases of the fins gradually approach the axis *x* from their outer ends to the center or plane *a*. This is clearly shown in Fig. 5, which is an enlarged section of Fig. 4 taken on the line V—V thereof. This characteristic is the result of cutting exteriorly into the wall of the liner in a path obliquely of its axis. The fins 15 and spaces 16, in addition to being provided by a simpler method, have the further advantage of being longer than the fins 6 and spaces 7 formed from the same size of collar *b*. Furthermore the fins 15 and spaces 16 being at an angle to the axis *x* produce a turbulence in the flow of the cooling water, thereby increasing the heat transfer rate.

The liner of Figs. 1 to 3 further includes a boss 17 which is formed by suitably cutting away the collar *b*. The boss is disposed between two of the fins 6 and has its center in the plane *a*. In cutting away the collar *b* to form the boss and portions of the two adjacent fins 6, three short fins 18 with adjacent spaces 19 are formed.

The jacket 2 snugly engages the boss 17. A similar boss 20, short fins 21, and adjacent spaces 22 are provided in the construction of Figs. 4 and 5, except that here the boss, short fins, and adjacent spaces are inclined similarly to the long fins and long spaces of this construction.

The boss is for the purpose of providing means for securing a fixture (not shown) to the cylinder assembly. There are several of these fixtures usually employed, such as fuel injectors, a glow plug, and a starting valve, and there will accordingly be a corresponding number of bosses provided, spaced circumferentially at the plane *a*. The liner at the bosses and the adjacent portions of the jacket will be suitably orificed (not shown) according to the requirements of the particular fixtures to be connected thereto.

While there have been hereinbefore described approved embodiments of this invention, it will be understood that many and various changes and modifications in form, arrangement of parts and details of construction thereof may be made without departing from the spirit of the invention and that all such changes and modifications as fall within the scope of the appended claims are contemplated as a part of this invention.

The invention claimed and desired to be secured by Letters Patent is:

1. An opposed-piston internal combustion engine power cylinder comprising a cylinder liner having external integral circumferentially-spaced heat transfer fins extending across the transverse center plane of the cylinder combustion chamber parallel to the axis of said liner, the liner in the spaces between said fins having its outer face at each side of said plane inclining inwardly toward said axis, said liner in said spaces thereby decreasing in thickness in a direction toward said plane and being of a minimum thickness substantially at said plane; and a jacket surrounding said liner, spaced therefrom at each end of said fins providing chambers and engaging said fins providing a sleeve therefor closing said spaces, the closed spaces providing passages connecting said chambers and said chambers being provided one with an inlet and the other with an outlet for the flow of a cooling fluid medium through said chambers and passages.

2. An opposed-piston internal combustion en-

gine power cylinder comprising a cylinder liner having external integral circumferentially-spaced heat transfer fins extending across the transverse center plane of the cylinder combustion chamber at oblique angles to the axis of said liner, the liner in the spaces between said fins having its outer face straight in a longitudinal direction and at an oblique angle to said axis in a plane parallel to said axis, said liner in 5 said spaces thereby, at each side of said plane, decreasing in thickness in a direction toward said plane and being of a minimum thickness substantially at said plane; and a jacket surrounding said liner, spaced therefrom at each 10 end of said fins providing chambers and engaging said fins providing a sleeve therefor closing said spaces, the closed spaces providing passages connecting said chambers and said chambers being provided one with an inlet and the other with an outlet for the flow of a cooling fluid medium through said chambers and passages.
